UNITED STATES PATENT OFFICE.

ARTHUR F. PYM, OF MARBLEHEAD, MASSACHUSETTS, ASSIGNOR TO UNITED SHOE MACHINERY CORPORATION, OF PATERSON, NEW JERSEY, A CORPORATION OF NEW JERSEY.

METHOD OF MAKING SHOES.

Original application filed January 7, 1921, Serial No. 435,636. Divided and this application filed March 21, 1924. Serial No. 700,843.

To all whom it may concern:

Be it known that I, ARTHUR F. PYM, a citizen of the United States, residing at Marblehead, in the county of Essex and 5 Commonwealth of Massachusetts, have invented certain Improvements in Methods of Making Shoes, of which the following description, in connection with the accompanying drawings, is a specification, like reference characters on the drawings indicating like parts in the several figures.

This invention relates to the manufacture of shoes and more particularly to the shaping of the upper materials over their lasts, 15 the present application being a division of a prior application Serial No. 435,636, filed on January 7, 1921.

The toes of shoes are commonly lasted in what are known as bed lasting machines by 20 the use of wipers shaped in accordance with the requirements of the different styles and sizes of shoes, this type of machine having means for adjusting the wipers in various ways, including means for varying relatively the pressures applied to the upper materials by the edges of the wipers at the end and the sides of the toe. It is the practice, 25 in making the wipers, to determine the curvature of their wiping edges by the use of a pattern having substantially the shape of the insole, so that the wipers are designed 30 substantially to fit the toe end of the insole. While this curvature is doubtless the best for practical purposes, having regard to the 35 conditions met with at different stages in the toe lasting operation, it will be evident that in view of the added thickness of the upper materials, wipers shaped in this manner will not exactly fit the toe of the shoe 40 in upwiping the upper over the last and the edge of the insole, nor on welt shoe work will they exactly conform to the different 45 curvature presented by the margin of the upper materials lying against the rib of the insole at the end of the overwiping operation. Moreover, further deviations from accuracy in the conformity of the edges of the wipers to the curvature of the toe may 50 result from the manner in which the wipers are adjusted by the operator. This may be due not only to lack of care on the part of an operator, but also to the fact that since the gathers or wrinkles in the margin of

the upper materials are more pronounced about the end of the toe than at the sides 55 of the toe, operators have a tendency to adjust the wipers to apply relatively greater pressure at the end of the toe, so that frequently the pressures applied at the sides are not fully adequate to wipe the upper tightly 60 over the last and the edge of the insole and to press it closely into the angle between the feather and the rib of the insole. When a shoe has been lasted in this manner, the upper is likely not to be held tightly in 65 the angle at the base of the insole rib at the sides of the toe by the welt-attaching stitches, and as a result in the sole leveling machine the upper may be pressed outwardly in these locations with substantial 70 detriment to the shape of the finished shoe.

The present invention provides an improvement in methods of making shoes whereby the above-mentioned undesirable 75 consequences are eliminated. For the purposes in view, the invention provides for applying to the toe of the upper, after it has been lasted in the usual manner, additional treatment to work it or wipe it heightwise of the last and to wipe or mold it inwardly over the insole. While the invention is not limited to treatment of the upper at the sides of the toe, it is herein illustrated by reference to treatment applied 80 in these locations only, since it is at the sides of the toe that the lasting is most likely to be deficient, as hereinabove explained. It is considered that the wiping of the upper heightwise of the toe and the wiping or molding of it inwardly over the insole may 85 be most effectively accomplished in the presence of heat which will shrink the upper enough to take up any slack produced by the supplemental wiping operation and thus make it unnecessary to disturb the 90 means whereby the upper is fastened in lasted position and will also assist in "setting" the upper in its acquired shape.

The novel method will now be more particularly explained by reference to the accompanying drawings and thereafter pointed out in the claims.

In the drawings,

Fig. 1 is a plan view of wiping means adapted for use in practicing the method of 105 this invention, this means being more fully

illustrated and described in its relation to other parts of an organized machine in my prior application of which this application is a division;

5 Fig. 2 illustrates the upwiping action at the sides of the toe of a lasted welt shoe;

Fig. 3 illustrates the later step of wiping and molding the upper into the angle between the feather and the rib of the insole and of applying molding pressure at the sides of the last, and

10 Fig. 4 is a perspective view to illustrate more fully the character of the operation shown in Fig. 3.

15 The method is herein illustrated as carried out by the aid of wiper members 2 which are pivoted at 4 upon wiper holders 6 so that they may turn about axes extending heightwise of the shoe to adapt their position to the lengthwise contour of the shoe. These wiper members have inwardly projecting portions adapted to be utilized first to engage and upwipe the upper at the sides of the toe, as illustrated in Fig. 2, and at a 20 later stage to wipe the upper inwardly over the feather of the insole and apply molding pressure in the angle between the feather and the rib, as illustrated in Fig. 3. The members 2 are also provided with shoe engaging faces 8 which apply molding pressure to the sides of the shoe exteriorly of the shoe bottom when these members are in the positions illustrated in Fig. 3, while at a 25 same time limiting the extent of inward movement of the members. During their operations on the shoe the wiper members 2 are heated to the required degree by electrical heating units 10 which are mounted therein.

30 The means whereby the wiper members 2 are operated and controlled, and the means whereby relative movements between these members and the shoe in the direction of the height of the shoe are effected, need not be described herein, since they are fully described in the copending application. Likewise the step of lasting the toe is not herein illustrated in detail, since it may be accomplished in the same manner as common heretofore and as well understood in the art.

35 It will be understood that a shoe having its toe end lasted and with the upper held in lasted position, for example by a binder wire, as shown, is so presented that the wiper members 2 when they are closed inwardly will engage the sides of the toe below the edge of the shoe bottom, substantially as illustrated in Fig. 2, and while the wiper members are thus pressing yieldingly against

40 the sides of the toe at and near the location of the tip seam, relative movement of the shoe and the wiper members is effected to cause said members to wipe the upper toward the edge of the insole and thus further to tighten it over the last in these loca-

tions. Thereafter the wiper members are closed inwardly over the feather of the insole toward and it may be against the toe binder wire *a* and its fastening tacks *t*, as illustrated in Figs. 3 and 4, thus wiping the upper inwardly and further tightening it as well as defining a better angle between the feather and the rib of the insole. The wiper members are then in position to apply molding pressure to the upper both on the sides of the toe at and below the edge of the insole and in the angle between the feather and the rib, and they will be held in these positions as long as is desirable to cause the upper to set in its newly acquired shape.

45 The heating of the wiper members 2 by the heating units 10 contributes further to the purposes in view, since the heat has a shrinking effect upon the leather which assists in taking up any slack produced by the supplemental wiping operation, so that it is unnecessary to disturb the upper fastenings or to apply additional fastenings after the upper has been subjected to the treatment of the members 2. It will also be understood that the application of heat likewise assists in molding the upper about the edge and over the feather of the insole.

50 Treatment in accordance with the method of this invention produces a toe which is tightly lasted at the sides as well as about the end of the last, and in which the angle in the margin of the upper between the feather and the rib of the insole is sharply defined at the sides of the toe as well as in other locations, thus permitting the welt and the upper to be secured tightly and closely at the base of the insole rib in the 100 inseam sewing operation.

55 While the invention is herein illustrated by reference to welt shoe work, for which it has very important advantages, it will be understood that it is not limited to that particular kind of work but may be used to advantage in the manufacture of other kinds of shoes.

60 Having explained the nature of the invention and set forth fully how it may be practiced, what I claim as new and desire to secure by Letters Patent of the United States is:—

65 1. That improvement in methods of making shoes which consists in lasting the toe of a shoe including the fastening of the upper in the angle between the feather and the rib of the insole, and thereafter working the upper over the toe of the last toward the edge of the insole and then inwardly into the angle between the feather and the rib of the insole to tighten the upper and conform it more closely to the last and to the contour of the insole.

70 2. That improvement in methods of mak-

ing shoes which consists in lasting the toe of a shoe including the fastening of the upper in the angle between the feather and the rib of the insole, and thereafter while the upper is held in lasted position by its fastening means wiping it heightwise of the last at the opposite sides of the toe and molding it in the angle between the feather and the rib of the insole to tighten it and to form a better angle to receive the upper securing stitches.

3. That improvement in methods of making shoes which consists in lasting the toe of a shoe including the fastening of the upper in lasted position, and thereafter while the upper is held in lasted position by its fastening means applying to the lasted toe portion of the upper wiping pressures directed heightwise of the last and inwardly over the bottom of the last to work the upper more closely and tightly into conformity to the contour of the last.

4. That improvement in methods of making shoes which consists in lasting the toe of a shoe including the fastening of the upper in lasted position, and after the upper has been fastened in lasted position wiping it heightwise of the last at the opposite sides of the toe and molding it in the angle between the feather and the rib of the insole while subjecting it to the action of heat to tighten it over the last and to prepare it for the inseam sewing operation.

5. That improvement in methods of mak-

ing shoes which consists in lasting the toe of a shoe including the fastening of the upper in lasted position over the feather and against the rib of the insole, and thereafter applying, at the opposite sides of the toe only, wiping and molding pressures to tighten the upper over the last and to define a better angle between the feather and the rib of the insole.

6. That improvement in methods of making shoes which consists in applying to the lasted toe portion of a shoe, while the upper is fastened in lasted position, both upwiping and overwiping pressures, and at the same time subjecting the upper to the action of heat, to tighten the upper over the last and to shape it in better conformity to the contour of the last and of the insole.

7. That improvement in methods of making shoes which consists in applying to the sides of the lasted toe portion of a shoe, after the upper has been fastened in lasted position in the angle between the feather and the rib of the insole, upwiping pressure toward the edge of the insole, and thereafter applying molding pressure both at the sides of the toe exteriorly of the shoe bottom and in the angle between the feather and the rib of the insole while subjecting the upper to the action of heat.

In testimony whereof I have signed my name to this specification.

ARTHUR F. PYM.
